UNITED STATES PATENT OFFICE.

HERBERT O. ROCKWELL, OF NEW BRITAIN, CONNECTICUT, ASSIGNOR TO THE B. & K. MANUFACTURING CO., OF NEW BRITAIN, CONNECTICUT, A CORPORATION OF CONNECTICUT.

DESIGN FOR A COMBINATION-TOOL.

53,613.

Specification for Design.

Patented July 15, 1919.

Application filed March 6, 1919. Serial No. 281,096. Term of patent 14 years.

To all whom it may concern:

Be it known that I, HERBERT O. ROCKWELL, a citizen of the United States of America, residing at New Britain, Connecticut, have invented a new, original, and ornamental Design for a Combination-Tool, of which the following is a specification.

In the drawing:

Figure 1 is a perspective view of a tool embodying my design.

Fig. 2 is another perspective view of the same tool taken from a different angle.

Fig. 3 is an end view.

I claim—

The ornamental design for a combination tool, substantially as shown.

HERBERT O. ROCKWELL.
